UNITED STATES PATENT OFFICE.

ELWIN H. KIDDER, OF CHICAGO, ILLINOIS, ASSIGNOR TO LINK-BELT COMPANY, OF CHICAGO, ILLINOIS, A CORPORATION OF ILLINOIS.

UNLOADING TOWER.

Application filed September 7, 1926. Serial No. 133,804.

My invention relates to improvements in unloading towers or hoisting mechanism for loading and unloading boats and the like. My invention is primarily intended 5 for use in connection with coal handling apparatus wherein a bucket is swung out over a boat in the slip, lowered into the hold, lowered, hoisted, carried back out of line with the boat and then dumped. One 10 of the objects of my invention is to provide a new and improved type of laterally projecting beam mounted on the tower which will be compact, sightly and inexpensive to manufacture. Another object is to provide 15 an operating mechanism whereby the lateral movement of the bucket may be provided. Other objects will appear from time to time throughout the specification and claims.

My invention is illustrated more or less 20 diagrammatically in the accompanying drawings, wherein—

Figure 1 is a side elevation;

Figure 2 is a section along the line 2—2 of Figure 1;

25 Figure 3 is a section along the line 3—3 of Figure 1;

Figure 4 is a section along the line 4—4 of Figure 1, with parts broken away; and

30 Figure 5 is a section along the line 5—5 of Figure 1, with parts broken away.

Like parts are indicated by like characters throughout.

A is a supporting tower which may be built exclusively for the purpose or may be 35 some other part of the building as the case may be. Mounted on this tower is a workhouse comprising vertical columns A¹ A² A³ and horizontal beams A⁴ A⁵. The structure of this workhouse may be of any suitable 40 arrangement provided only that it has sufficient strength to carry the load. Projecting laterally from the workhouse structure is a cantilever girder A⁶. This cantilever girder carries the parallel tracks A⁷ A⁷, extending 45 from the outermost part of the girder into the interior of the workhouse as indicated.

Mounted on the bottom floor of the workhouse is a hoisting machine A⁸ and on an upper floor a trolley machine A⁹. Beneath 50 the workhouse mounted on the tower A is a hopper A¹⁰, this hopper being located beneath the inner ends of the track A⁷. At either end of the tracks A⁷ are spring buffer plates A¹¹ A¹² to limit the excursion of the 55 trolley along the tracks.

B is a main trolley wagon mounted on flanged wheels B¹ B¹ adapted to travel along the tracks A⁷. This trolley wagon hangs down on the wheels between the tracks and has the two sheaves B² B³ over which are 60 adapted to travel respectively the hoisting rope B⁴ and the hold rope B⁵. B⁶ is an auxiliary trolley wagon mounted on flanged wheels B⁷ traveling along the tracks A⁷. But this wagon is located primarily above 65 the tracks. It has sheaves B⁸ B⁹ over which are respectively adapted to travel the hoisting rope B⁴ and the hold rope B⁵. It will be noted that the upper portion of the 70 sheaves on the main trolley wagon are substantially in line with the lower portion of the sheaves or pulley wheels on the auxiliary trolley wagon. The hoisting rope and hold rope pass inwardly along the cantilever beam being supported by the sheaves B¹⁰ intermediate the ends of the beam to the pulley 75 wheels B¹¹ B¹² on the vertical column B¹³ in the workhouse and thence down to the drums B¹⁴ B¹⁵ in the hoist machine. These two 80 ropes together support the hoisting bucket and manipulation of them permit automatic 85 filling and emptying of the bucket. The bucket itself is shown diagrammatically as at D². The details of the bucket and the means by which it is operated and controlled 90 are not illustrated as its forms no part of the present invention.

The hoisting and hold ropes riding over the pulleys on the main trolley wagon and extending outwardly on the auxiliary pulley 95 wagon tends when there is any tension on these ropes to move the main trolley wagon toward the outer end of the cantilever structure. This movement is resisted by the trolley rope C anchored on the main trolley wagon 100 B, extending inwardly along the cantilever structure, guided by the roller or shaft C¹ to the drum C² in the trolley machine. The trolley rope is wound about this drum in a clockwise direction and is dead ended thereon.

The hoisting and hold ropes extending outwardly from the tower and wrapped as they are around the sheaves on the auxiliary trolley wagon and extending back inwardly 105 as they do to travel around the sheaves on the main trolley wagon, exert a force tending to move the auxiliary trolley wagon inwardly toward the tower toward the track. This force is exerted by the auxiliary trolley 110

rope C³ which is wound around the drum C² in a counter clockwise direction and dead ended thereon. This rope extends out over the sheave C⁴ on the beam B¹³ along the 5 cantilever arm, being guided by the pulleys C⁵ to the differential drum C⁶ where it is wound around the larger diameter as at C⁷ in a clockwise direction, being dead ended thereon. The differential drum has on either 10 side of the larger diameter section C⁷ smaller drum sections C⁸ all mounted together for rotation in unison on the shaft C⁹ in the bracket C¹⁰ on the outer end of the cantilever. C¹¹ is an equalizing beam pivoted on 15 the auxiliary trolley wagon B⁶. Cables C¹² C¹² extend from either end of this equalizing beam and are wound about the smaller diameter C⁸ of the differential drum in a counter clockwise direction, being dead 20 ended thereon. The arrangement is such that when the auxiliary trolley rope is drawn in by the rotation of the drum C² in a counter clockwise direction, the differential drum is also rotated in a counter clockwise 25 direction and the two ropes C¹² leading from the differential beam are wound in moving the auxiliary trolley wagon toward the outer end of the cantilever arm. The relative proportions of the drum members 30 C⁷ C⁸ is such that the auxiliary trolley wagon moves half as fast as the rope, that is, for each rotation of the drum C⁷ the ropes C¹² move a distance equal to one-half the length of rope C³ which is wound about the 35 drum C⁷.

Thus when the drum C² is rotated in a clockwise direction, it tends to move the trolley wagon to the left by winding up the trolley cable C. At the same time it pays 40 out at the same rate of speed on the auxiliary trolley cable C³ and permits the differential drum to rotate in a clockwise direction. When this happens the auxiliary trolley wagon is permitted to move to the left at a 45 rate of speed half as great, half as fast, as the movement of the main trolley wagon. If the hoisting and hold ropes are held fast, movement of the main trolley wagon alone to the left with the auxiliary trolley wagon 50 at rest would result in drawing up on the hoisting and hold ropes and raising the buckets at the same rate of speed as the movement of the main trolley wagon but since at the same time the auxiliary trolley 55 wagon follows the main trolley wagon this tends to pay out on that part of the hoisting and hold ropes between the auxiliary trolley wagon and the tower and would tend to pay out the hoisting and hold ropes at the same 60 rate of speed as the movement of the auxiliary trolley wagon. The differential movement of the two trolley wagons results in permitting them to move back and forth along the cantilever without paying out on 65 the hoisting and hold ropes as far as the

bucket is concerned and thus the bucket can be moved laterally by manipulation of the trolley ropes without manipulation of the hoisting and hold ropes.

The bucket can thus be filled by lowering 70 it into the hold of a vessel, manipulating the hoisting and hold ropes. The bucket can thus be hoisted until it is in a position above the level of the hopper A¹⁰ with the trolley in the position shown in the drawings, then 75 without further manipulation of the hold rope, the trolley can be moved inwardly, moving the bucket laterally until it hangs above the hopper without changing its level so that it can be dumped and its contents 80 discharged into the hopper.

It will be understood that the reason for this operation of the bucket is that the differential movement of the two trolley wagons is such that the paying out of the 85 rope caused by the movement of one is counter-balanced by the drawing in of the rope caused by the separation of the two wagons.

The relation between the main and auxiliary trolley ropes is such that at no time do the two trolleys actually come in contact because when they are in the position shown in the figures with the auxiliary trolley at the right hand end of its excursion it is 90 cushioned by the bumper bar and can go no further, thus the trolley ropes will not be paid out any further and the wagons are held in proper separated position.

When the wagons are in their inner position, the main trolley wagon is limited by the buffer and the auxiliary trolley wagon has gone half way in as indicated in dotted lines. The tension of the two trolley ropes is counter-balanced each by the other and by 105 the pull of the hoisting and holding ropes so that all that is necessary to manipulate the trolley is the electric motor shown at D under the control of the operator by any suitable electric power not here shown. The 110 hoisting and hold ropes are controlled through the motor D¹, the control mechanism for which is also not shown as neither of these control mechanisms forms a part of my present invention.

It will be evident that while I have shown in my drawings an operative device, still many changes might be made in the size, shape, arrangement and disposition of parts without departing from the spirit of my invention, and I wish, therefore, that my showing may be taken as in a sense diagrammatic.

I claim:

1. A hoisting mechanism comprising a 125 laterally extended track, a plurality of trolley wagons thereon, sheaves carried by said wagons, a fixed sheave at one end of the track, a hoisting engine, a hoisting rope extending from the engine over the fixed 130

sheave, thence along the track and over the sheave on the trolley wagon furthest from the fixed sheave, thence back over the sheave on the intermediate trolley wagon and thence 5 downward to a bucket, a trolley engine, a differential trolley drum rotatably mounted at the end of the track opposed to the fixed sheave, a trolley rope extending from the engine and wound about the larger radius 10 of the drum, a differential trolley rope wound about the smaller radius of the drum and anchored on the trolley wagon nearest thereto, a second trolley rope extending in the opposite direction from the engine and 15 anchored on the other trolley wagon.

2. A hoisting mechanism comprising a boom, a track horizontally disposed thereon, trucks mounted for travel along the track, sheaves carried by the trucks and fixed 20 sheaves mounted on the boom adjacent the inboard and the outboard ends of the track, a hoisting cable extending from the inboard

sheave along the track about the sheave on the outboard truck, thence back about the sheave on the inboard truck and thence depending downwardly therefrom, a shifting motor adjacent the inboard end of the track, a shifting cable dead ended on the inboard truck extending thence inwardly to the shifting motor, a second shifting cable extending 30 from the shifting motor outwardly along the track wound about and dead ended on the outboard fixed sheave, a pair of drums associated with the outboard sheave of smaller diameter than the sheave and mounted for 35 rotation therewith, cables dead ended on each of said drums and wound about them and extending in parallel to and dead ended on the outboard truck.

Signed at Chicago, county of Cook, and 40 State of Illinois, this 23rd day of August, 1926.

ELWIN H. KIDDER.
